UNITED STATES PATENT OFFICE.

HARRY U. MORTON, OF CHICAGO, ILLINOIS, ASSIGNOR TO MORTON MANUFACTURING COMPANY, OF CHICAGO, ILLINOIS, A CORPORATION OF ILLINOIS.

EXTENSIBLE CURTAIN ROLLER.

Application filed October 18, 1920. Serial No. 417,583.

To all whom it may concern:

Be it known that I, HARRY U. MORTON, a citizen of the United States, and a resident of the city of Chicago, in the county of Cook 5 and State of Illinois, have invented certain new and useful Improvements in an Extensible Curtain Roller; and I do hereby declare that the following is a full, clear, and exact description of the same, reference being had 10 to the accompanying drawings, and to the numerals of reference marked thereon, which form a part of this specification.

This invention relates to an extensible curtain roller and particularly to an extensible roller for vestibule curtains for passenger cars which is ordinarily spring actuated to automatically wind said curtains thereon. On account of the varying distance between 15 the brackets on which curtain rollers are used, it is desirable that said rollers be of such construction that the length thereof may be conveniently adjusted. It is also desirable that these rollers be durably constructed and that means be provided for securely locking same in adjusted position.

It is an important object therefore of this invention to provide an extensible curtain roller of durable construction which may be conveniently and securely locked in adjusted 20 position.

It is also an important object of this invention to provide a telescopic curtain roller which may be adjusted longitudinally and which is locked in adjusted position by means 25 frictionally engaging the inner telescopic portion.

Other and further important objects of this invention will be apparent from the disclosures in the specification and the accompanying 30 drawings.

The invention (in a preferred form) is shown in the drawings and hereinafter more fully described.

On the drawings:

Figure 1 is a view in elevation of the extensible curtain roller of this invention with a curtain thereon.

Figure 2 is a fragmentary elevation of the curtain roller.

Figure 3 is a section on the line 3—3 of Figure 2.

Figure 4 is a fragmentary section on the line 4—4 of Figure 3.

As shown on the drawings:

The extensible curtain roller of this in-

vention ordinarily comprises telescopic cylindrical sections 1 and 2 which are preferably formed from stamped or drawn metal, the section 2 being slidably engaged inside the section 1. Said inner section 2 is provided with an inwardly extending integral portion 3 affording a longitudinal slot 4 and the inner edges of said portion 3 are bent horizontally to form flanges 5, as clearly shown in Figures 3 and 4. Said flanges 5 extend inwardly toward the inner face of the portion 2 but at no point contact said inner face. Means are provided for locking the telescopic portions 1 and 2 in adjusted position. For this purpose a countersunk aperture is provided in the portion 1 above the slot 4 and engaged in said aperture is a machine screw 6 which extends downwardly through the slot 4 and is engaged through a threaded aperture in a rectangular plate 7 which is adapted to engage the underside of the flanges 5. Said plate 7 engages the under surface of said flanges 5 but does not extend beyond the edges of the same and does not contact the inner walls of the member 2 when in adjusted position. It is of course apparent from the foregoing that the members 1 and 2 are locked in adjusted position by simply tightening the screw 6 whereby the plate 7 is drawn upwardly against the flanges 5 and frictionally engages the same. While the members 1 and 2 are held tightly together by the tightening of the screw 6 and the drawing thereon of the plate 7 there is no wedging action and no distortion or expansion of the inner member 2. The head of the screw 6 is preferably rounded so that when it is engaged in the countersunk aperture in the member 1 it does not make an obstruction on the outside of the curtain roller. Integral internal ridges 8 and 9 are formed on the members 1 and 2 respectively and engaged in the groove formed by the ridge 8 is a rod or wire 10 which acts to lock the edge of a curtain 11 therein and secure the curtain upon the roller.

The curtain roller is ordinarily provided with the usual spring arrangement whereby the curtain is automatically wound thereon but since this spring arrangement constitutes no part of this invention it need not be described in detail herein.

The curtain roller provided by this invention is simple and easily constructed and the locking means provided therefor are easily

2
operated and since said locking means do not act to expand the inner member 2 it is always easy to move said members 1 and 2 relative to each other when it is desired to adjust the 5 roller.

I am aware that numerous details of construction may be varied through a wide range without departing from the principles of this invention and I therefore do not purpose limiting the patent granted otherwise than necessitated by the prior art. 10

1 claim as my invention:

1. An extensible curtain roller comprising a pair of tubular telescoping portions, 15 the inner portion having a longitudinal slot therein, the walls of said inner tube being turned inward adjacent the edges of said slot to form inwardly extending thrust receiving means, flanges integral with said inwardly extending means, said flanges being perpendicular to said means, and a clamping device including a part adapted to contact said flanges and a part adapted to contact the 20

outer tubular portion, said clamping device exerting a pressure against said flanges to 25 create a thrust in said thrust receiving means to cause said inner and outer tubular portions to be clamped together to hold the roller at the selected length.

2. An extensible curtain roller comprising 30 a pair of telescopic portions, the inner one of said portions having two inwardly extending members spaced apart, and means extending through the space between said members for clamping the portions together, 35 said inwardly extending members being in planes substantially parallel to the line of action of said clamping means.

In testimony whereof I have hereunto subscribed my name in the presence of two 40 subscribing witnesses.

HARRY U. MORTON.
